Primary Examiner — John Windmuller(74) *Attorney, Agent, or Firm* — Brinks Hofer Gilson & Lione(57) **CLAIM**

We claim the ornamental design for a remote control for television apparatus, as shown and described.

DESCRIPTION

FIG. 1 is a front perspective view of a remote control for television apparatus of the present invention;
 FIG. 2 is a rear perspective view thereof;
 FIG. 3 is a front view thereof;
 FIG. 4 is a rear view thereof;
 FIG. 5 is a first side view thereof;
 FIG. 6 is a second side view thereof;
 FIG. 7 is a top view thereof; and,
 FIG. 8 is a bottom view thereof.
